UNITED STATES PATENT OFFICE.

JOSEPH A. READ, OF PHILADELPHIA, PA., ASSIGNOR TO GILBERT COMBS,
JOHN BAWDEN, AND JOHN H. BAWDEN, ALL OF FREEHOLD, N. J.

DESIGN FOR A FIRE-PLACE FRAME.

SPECIFICATION forming part of Design No. 14,169, dated August 14, 1883.

Application filed May 5, 1883. Term of patent 14 years.

To all whom it may concern:

Be it known that I, JOSEPH A. READ, a citizen of the United States, and a resident of Philadelphia, Pennsylvania, have invented or produced a new and original Design for a Fire-Place Frame or Border, of which the following is a specification.

My design is fully shown in the accompanying photograph.

10 The frame comprises opposite side panels and a top panel. At the base of each side panel is a representation of a log, and springing from the same and extending to the top of the panel is a leafy stalk, on which birds are perched. At the top of each side panel is an arched cap. The upper panel has a central floral ornament, and on each side of the latter conventionalized stems, leaves, and blossoms, of a character too clearly shown to need description. It is immaterial to the design whether the corners of the frame be square, as shown, or be made round, the essential features of the ornamentation remaining the same.

I claim—

1. The design for the side panels, said design comprising the representation of a stalk with birds perched thereon, as shown and described. 25
2. The design for the side panels, said design comprising the representation of a stalk with birds perched thereon, and the arched cap at the top of the panel, as shown and described. 30
3. The design for the top panel, said design comprising the central floral ornament and opposite side ornamentation, as shown and described. 35
4. The design for a fire-place frame or border, said design comprising the side panels and top panel with ornamentation, as shown and described. 40

In testimony whereof I have signed my name to this specification in the presence of two subscribing witnesses.

JOSEPH A. READ.
